ROBERT W. CONN, OF CRANSTON, RHODE ISLAND, ASSIGNOR TO WESTINGHOUSE LAMP COMPANY, A CORPORATION OF PENNSYLVANIA

SELF ADJUSTING BASE AND BULB HOLDER

Application filed June 15, 1929. Serial No. 371,230.

This invention relates to machines for manufacturing electrical devices and relates more particularly to a mechanism for holding a plurality of work parts in axial alignment.

5 In the manufacture of electrical devices such as radio tubes or the like which comprise a sealed envelope and a base portion, it is necessary to provide mechanism for 10 securing the base to the envelope or bulb. In the operation of attaching a base to a bulb it is important that the base be so positioned as to be substantially in axial alignment with the longitudinal axis of the bulb, 15 in order that a symmetrical and marketable product be obtained.

In the production of radio tubes, for example, the mode of attaching a base to a bulb usually includes the deposit of a ring of 20 basing cement about the inner wall and adjacent to the perimeter of the open end of the base. The neck of the bulb is then inserted into the base so that the cement is compressed between the base wall and the bulb. 25 When so positioned the base and bulb are passed through a baking oven so that the cement will set and securely adhere to the bulb and base thus firmly attaching the two work parts together.

30 It is the practice to provide bases with a quantity of cement properly positioned therein in which bases are then disposed upon the bulb neck and applied to a suitable holder.

It is an object of the present invention to 35 provide a holder wherein a base and bulb may be temporarily supported and automatically adjusted in axial alignment.

Another object of the invention is to provide a holder of simple construction which 40 may be conveniently and expeditiously operated to automatically adjust and retain a plurality of work parts in predetermined relative positions.

45 Although the present invention may be employed for supporting and aligning the component parts of various types of electrical devices the selected embodiment of the invention illustrates a construction wherein 50 a sealed envelope or bulb is held and auto-

matically aligned with a base having the usual projecting contact pins.

Briefly the present construction comprises a bearing bracket for a vertically reciprocal centering member to receive the spherical portion of a bulb. The bulb with a base loosely disposed on the neck portion thereof is positioned on the centering member and the base portion of the bulb is disposed adjacent to a retainer member, with which the contact pins of the base engage. Means are provided for tensionally engaging the centering member so that the bulb and base are normally urged to bring the base in contact with the retainer member and thus temporarily hold the base and bulb in position for subsequent adjustment. Intermediate the retainer member and the centering member, is provided a base and bulb adjusting means so that when the bulb and base are in position, said adjusting means may be actuated to adjust the base to a predetermined position and align the bulb to position its longitudinal axis coincident with the longitudinal axis of the base. A bulb so supported is properly aligned and ready to be moved to position for subsequent operations.

The invention will be more understood and other advantages and objects will be more fully appreciated from the following description together with the accompanying drawings, in which

Fig. 1 is a fragmentary plan view of a portion of a conveyor having a plurality of 85 heads or holders thereon constructed in accordance with the present invention.

Fig. 2 is an enlarged front view of a head ready to receive a bulb and base.

Fig. 3 is a view of the head taken on line 90 III—III in Fig. 2 and showing a base and bulb in dotted lines ready to be positioned in the head.

Fig. 4 is a view similar to Fig. 2 but showing the head with a bulb and base positioned therein.

Fig. 5 is a plan view of a head.

Fig. 6 is a view taken on line VI—VI in Fig. 4.

Fig. 7 is a view taken on line VII—VII in Fig. 4.

Fig. 8 is a view taken on line VIII—VIII in Fig. 4.

Fig. 9 is a view taken on line IX—IX in Fig. 4.

Fig. 10 is a side view of one of the heads showing a bulb with a bulb centering member shown in dotted lines in its lower position, and

Fig. 11 is a perspective view of a base having cement therein ready to be applied to the neck of a bulb.

The present invention relates to what is generally termed a basing head and is indicated as a whole by the reference numeral 15. A plurality of these heads may, as shown in Fig. 1, be mounted in close spaced relation on the periphery of a conveyor 16.

The conveyor may be provided with the usual mechanism (not shown) for causing a rotation thereof either continuously or intermittently. A radio tube comprising a base 17 and a bulb 18 may be inserted in a head at the loading position A. The base may be provided with a ring of cement 19 so that when the base is disposed upon the bulb neck the cement will serve as an intermediate bonding medium when baked by a travel of the bulb and base through a heating oven.

The bulb may be provided with lead wires 21 which are threaded through tubular contact members 22 of the base so that when the base and bulb have been secured by the cement a subsequent operation may be performed for soldering the lead wires to the contact members or pins 22. After passing through the oven the bulb with the base attached thereto is discharged at B.

It will be evident from the above that it is necessary to provide suitable means whereby the base is properly aligned with respect to the bulb so that when the two parts become a unitary structure they will have the desired symmetrical appearance. For the purpose of properly aligning and holding the work parts together the head 15 is provided with a centering member 23 having a plurality of inclined contact surfaces 24 arranged to provide a three point contact for the spherical surface or bowl 25 of the bulb 18. The centering member 23 is mounted at the upper end of a slide rod 26 movable vertically in bearings 27 and 28 of a bearing bracket 29.

This bracket may be secured by tap bolt 31 to the conveyor 16.

For the purpose of effecting a tensional engagement between the centering member 23 and the bulb, the rod 26 is provided with an offset member 32 having an extension 33 provided with an aperture 34 through which the slide rod 26 extends. A helical spring 35 is disposed between the extension 33 and the bearing 28. The lower end of the offset member 32 is provided with a projection 36

having an aperture 37 to receive the lower end 38 of the slide rod 26. The lower end of the slide rod is provided with a plurality of transverse apertures 39 to receive a cotterpin 41 which may be passed through aperture 42 in the extension and through an aperture 39 in the rod.

By adjusting the slide rod and placing the cotterpin 41 in one or the other of the apertures 39 the position of the centering member 23 may be varied so as to accommodate bulbs of different dimensions.

The projection 36 is provided with an upwardly projecting guide pin 43 which is movable in an extension bearing 44 so that a vertical reciprocation of the slide rod 26 may be attained without rotary movement thereof. A roller 45 may be provided on the extension 36 for engagement with a cam surface 46 so that at the proper position during a movement of the conveyor 16, the offset member 32 may be moved to lower the centering member 23 to receive a bulb. If desirable, however, the offset member may be manually operated and for this purpose a finger piece 47 is provided.

The foregoing description relates to the mechanism for receiving the spherical portion of the bulb. When the top or bowl portion of the bulb is disposed in the centering member 23, however, the base portion is moved to bring the contact pins 22 into engagement with the surface of a slot 48 provided in a plate 49 (see Fig. 5) and as the bulb 18 is urged upwardly under the action of the spring 35, the bottom surface 51 of the base is moved into contact with the lower surface 52 of the said plate 49, thus the bulb and base are temporarily held in position.

The plate 49 is mounted at the upper ends of posts 53 and 54, the lower ends of the said posts being suitably secured in a cross piece 55 integral with the bracket 29. For the purpose of aligning the base as well as the bulb a movable member 56 may be provided. This member is secured to one end of a pedestal 57 extending from a cross head 58, the said cross head being provided with bearings 59 and 61 slidably upon the posts 53 and 54 respectively.

The member 56 which may be termed an alignment or adjuster element is provided with four upwardly projecting lugs 62 having surfaces 63 forming with the curvature of the cylindrical portion of the base and so arranged as to make contact with the base when the said member 56 is moved downwardly. When the member 56 is in its upper position the lugs 62 project through suitably disposed apertures 60 in the plate 49.

The member 56 may be provided with a roller 64 mounted on the cross head 58 and a cam 65 suitably disposed with respect to the path of movement of the conveyor 15 may be provided for engaging the said roller 64. The cam 65 may have a contact surface of such

formation that when the head 15 is in the loading position the member 56 will be moved up into contiguous relation with the plate 49, thus permitting the bulb to be positioned and held between the centering member 23 and the plate 49.

As the conveyor moves the surface 66 of the cam 65 causes the cross head 58 to move downwardly thereby lowering the adjuster member 56 and bringing the surfaces 63 of the lugs 62 in contact with the surface of the base, whereby the same is adjusted to a predetermined position.

The member 56 is provided with an annular recess in the lower surface thereof which forms a ledge. When the member is lowered the ledge engages shoulder 68 of the bulb and since the bulb and base are movable with relation to each other the said ledge 67 operating in conjunction with the centering device 23 adjusts the bulb so that its longitudinal axis is substantially coincident with the longitudinal axis of the base. The adjuster member 56 may be held in this lowered position by reason of the formation of the cam 65 while the bulb and base are passed through the baking oven. After the baking operation has been performed and the bulb is moved to position for discharge the cam 65 may cause an upward movement of the member 56 to its initial position.

The bulb is then in position to be discharged, which discharge may be accomplished by hand through a downward movement of the member 32 by engagement with the finger piece 47. The discharge may, however, be accomplished automatically by an engagement between the cam surface 46 and the roller 45, at which time a suitable valve 40 may be automatically opened to permit a discharge of air under pressure from nozzles 70 and 71 provided on an air conduit 72 (see Fig. 1). When the air jet discharge is employed, the bulb may be projected into a chute or 45 guide 74 leading to a suitably disposed receptacle not shown.

The bulb with the base connected therewith may, however, after being released, be removed by suitable mechanism and transferred to another machine for the next operation, as for example, the operation of soldering the lead wires to the contact members of the base.

From the foregoing it will be evident that 55 by reason of the present invention a base may be disposed upon a bulb neck and positioned in a holder which will automatically adjust the base to a predetermined position and align the bulb in proper relation to the base for attachment thereto.

Although a preferred embodiment of the invention is shown and described herein it is to be understood that modifications may be 65 made therein without departing from the

spirit and scope of the invention as set forth in the appended claims.

What is claimed is:

1. A device for holding a plurality of work parts in alignment comprising contact surfaces for engaging one part with its longitudinal axis in a given position, means for temporarily supporting another work part with its longitudinal axis in a given position, and means for aligning said second work part with its longitudinal axis coincident with the axis of said first part. 70

2. A bulb and base aligning device comprising means for holding a base, means for holding a bulb adjacent to said base, means for adjusting a base, and means for readjusting said bulb and base to bring their longitudinal axis in coincidence. 80

3. A bulb and base aligning device comprising base holding means, means for adjusting said base in said holding means, bulb supporting means and means for actuating said bulb supporting means to adjust said bulb for alignment with said base. 85

4. A bulb and base aligning device comprising means for supporting a bulb having a base loosely disposed on the neck portion thereof, means for engaging the base and means for changing the relative positions of said first and last mentioned means to adjust 90 said bulb and base to axial alignment. 95

5. A bulb and base aligning device comprising a bulb centering member, a member for engaging a portion of said base, a base aligning member means for actuating said aligning member to adjust the base with respect to said bulb and means cooperating with said bulb centering member for aligning said bulb with said base. 100

6. A head for holding a bulb and base comprising means for engaging a portion of a base disposed on a bulb neck, means for engaging a portion of said bulb and means for actuating said respective engaging means to adjust said bulb and base in predetermined 110 relation. 105

7. A head for holding a bulb having a base loosely disposed on the neck thereof comprising a base pin engaging member, a bulb engaging member, and means intermediate said members for adjusting said base and bulb to bring their longitudinal axes substantially in alignment. 115

8. A head for holding a bulb having a base loosely disposed on the neck thereof comprising means for engaging a portion of said base, means for engaging said bulb and means intermediate said respective engaging means for adjusting said base and bulb to axial alignment. 120

9. A device for holding a bulb with a base disposed on the neck portion thereof comprising bulb centering means, base adjusting means and means for aligning said base and bulb in a common axial line. 125 130

10. A device for holding a bulb with a base disposed on the neck portion thereof comprising bulb centering means, base retaining means and means intermediate said first and second mentioned means for aligning said base and bulb on a common axial line.
11. A device for holding a bulb with a base disposed on the neck portion thereof comprising a retainer-member for said base, a centering-member for said bulb, means for adjustably retaining said base between said retainer-member and said bulb and means for adjusting said bulb and base in axial alignment.
12. A device for holding a bulb with a base disposed on the neck portion thereof comprising a retainer-member for said base, a centering-member for said bulb, a plurality of contact surfaces for engaging and adjusting said base to a predetermined position and a bulb engaging surface for adjusting said bulb in axial alignment with said base.
13. A device for holding a bulb with a base disposed on the neck portion thereof comprising a retainer-member for said base, a centering-member for said bulb, means for adjustably retaining said base between said retainer-member and said bulb and means for adjusting said bulb and base in axial alignment and means for discharging said base and bulb.
14. A head for holding a base and bulb comprising a bulb centering member, means for tensionally holding said member in contact with a bulb having a base disposed on the neck portion thereof, a member for engaging the contact pins of said base to temporarily hold the same in position on said bulb, means for adjusting said base to a predetermined position and means for adjusting said bulb in axial alignment with said base.
15. A head for holding a bulb having a base loosely disposed on the neck portion thereof, comprising a support for said bulb, a plurality of contact-surfaces on said support for receiving and centering the spherical portion of said bulb, a contact-surface for engaging said base, means for maintaining said contact-surfaces engaged with said bulb to retain said base against said contact-surface, means for adjusting said base to a predetermined position and means for aligning said bulb with said base.

In testimony whereof, I have hereunto subscribed my name this 6 day of June, 1929.

ROBERT W. CONN.
